US00D560284S

(12) **United States Design Patent** (10) Patent No.: **US D560,284 S**
Nagakubo et al. (45) Date of Patent: **** Jan. 22, 2008**

(54) **COVER RING**

JP 1207599 6/2004
JP 1210213 6/2004

(75) Inventors: **Keiichi Nagakubo**, Nirasaki (JP); **Daiki Satoh**, Nirasaki (JP)

(73) Assignee: **Tokyo Electron Limited**, Tokyo (JP)

* cited by examiner

(**) Term: **14 Years**

Primary Examiner—Robert A. Delehanty

Assistant Examiner—Mark Cavana

(21) Appl. No.: **29/233,657**

(74) Attorney, Agent, or Firm—Oblon, Spivak, McClelland, Maier & Neustadt, P.C.

(22) Filed: **Jul. 8, 2005**

(57) **CLAIM**

(30) **Foreign Application Priority Data**

The ornamental design for a cover ring, as shown and described.

Mar. 30, 2005 (JP) 2005-009490

(51) LOC (8) Cl. **24-01**

(52) U.S. Cl. **D24/232**

(58) **Field of Classification Search** D24/187, D24/216, 224, 232; D15/122, 138, 144, D15/199; D16/134, 219; 118/715, 728; 156/345.51; 435/305.4; 414/609; D13/182

See application file for complete search history.

FOREIGN PATENT DOCUMENTS

JP 3424903 10/1998

FIG. 1 is a front elevational view of a cover ring, showing our new design;

FIG. 2 is a right side elevational view thereof, the left side elevational view being a mirror image of the view shown;

FIG. 3 is a top plan view thereof, the bottom plan view being a mirror image of the view shown;

FIG. 4 is a rear elevational view thereof;

FIG. 5 is a cross-sectional view thereof taken along line 5—5 in FIG. 1;

FIG. 6 is a bottom and front view thereof;

FIG. 7 is a cross-sectional view thereof taken along line 7—7 in FIG. 1; and,

FIG. 8 is a cross-sectional view thereof taken along line 8—8 in FIG. 1.
